UNITED STATES PATENT OFFICE.

WILLIAM A. MACOMB, OF STAMFORD, NEW YORK.

CAR-COUPING.

SPECIFICATION forming part of Letters Patent No. 367,819, dated August 9, 1887.

Application filed May 13, 1887. Serial No. 238,029. (No model.)

To all whom it may concern:

Be it known that I, WILLIAM A. MACOMB, a citizen of the United States, residing at Stamford, in the county of Delaware and State of New York, have invented certain new and useful Improvements in Automatic Car-Couplers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention has for its object to provide a novel and simplified construction in car-couplers, whereby when the cars are brought together they will couple automatically notwithstanding the various heights of the cars; and it consists in providing the coupler with a number of movable dogs the bearings of which work upon each and operate entirely by gravity, the bearings of which are placed in upright grooves cut upon the interior of the draw-head near its mouth, sufficient space being allowed between the forward end of them for the admission of the coupling-link; and it also consists in forming upon the top of the draw-head two lugs, which form bearings for the removable cover or top, provided with lugs for the purpose of replacing the dogs when they become broken or displaced, and also other details of construction, which will be hereinafter more fully shown and described.

In the accompanying drawings, in which corresponding parts are designated by similar letters, Figure 1 represents a vertical section of my complete invention in a proper position for coupling. Fig. 2 is also a vertical section with dogs detached. Fig. 3 is a front elevation of the draw-head. Figs. 4 and 5 are perspective views of the dogs; and Fig. 6 is the removable cover or top piece.

Referring to the drawings, A represents a draw-head of ordinary construction, and having formed within the same, leading from its mouth, a rounded lip, a, for guiding or directing the link to its proper position. The draw-head has also formed upon its inner surface, leading from the lip a, two upright grooves, a', and extending to the top of the same, for receiving the bearings of the dogs. B represents the dogs having formed upon

each side bearings b, which work in the upright grooves a', the opposite ends tapering in thickness, which causes the same to drop by gravity in their proper or normal position. These bearings are of circular form and of larger diameter than the dogs, and are placed within the grooves a', which cause them to work upon each other, leaving sufficient space between the dogs at the entrance of the coupling for the admission of the coupling-link.

The upper dog, B', is constructed somewhat differently from the remaining ones, for the purpose of holding the coupling-pin in its proper position before the cars come together. To this end the said dog is provided upon its face with an inclined groove, b', which serves as a bearing-surface for the end of the coupling-pin when the coupler is set for coupling, and which leads to a circular opening, b'', sufficiently large enough for the passage of the pin. This dog has also formed upon its under surface a lip, which causes any one of the dogs when forced upward in coupling to either directly or indirectly raise the same to a horizontal position and allow the coupling-pin to fall freely through the remaining dogs. The remaining dogs B have slots or holes sufficiently large enough to allow the pin to drop through the same, notwithstanding the angle to which they may be subjected in coupling.

To the top of the draw-head A are secured two uprights or bearings opposite each other, which receive the hinge-cover C. This cover is hinged to the upright by means of a bolt, and having its rear end beveled upon its lower surface for allowing the same to be raised at a sufficient height for the purpose of placing or removing the dogs when they become displaced or broken through the rough usage to which they may be subjected, said cover fitting into a recess or opening in the top of the draw-head and resting upon the bearing of the dogs, causing them to retain their proper position. This cover has also provided upon its lower surface, at a suitable distance from its forward end, two lugs, c, which enter the interior of the draw-head, and against which the dog B' is forced in coupling.

By this construction it will be observed that cars of different heights can be successfully coupled, as the link in entering the mouth of the draw-head is also directed between the

dogs, causing the remaining ones above the link to assume a horizontal position and allow the pin to fall and couple.

A further object of my invention is to avoid 5 the use of springs in connection with the operating parts, they being uncertain in their action and liable to become broken during the rough usage to which all couplers are necessarily subjected, and to effect a better result entirely by gravity, by means of which the parts operate promptly and reliably.

Having now fully described my invention, what I claim, and desire to secure by Letters Patent of the United States, is—

15 1. In a car-coupler, the combination of a draw-head having upright grooves for receiving the bearings of the dogs, the upper one having a lip formed upon its under surface and provided upon its face with an inclined 20 groove leading to a circular opening, and the remaining dogs provided with slots or recesses, as and for the purpose described.

25 2. In a car-coupler, the combination of a draw-head provided with two vertical recesses for receiving the bearings of the dogs, said dogs having slots or holes for the passage of the coupling-pin, and a removable cover hinged upon the top of the draw-head, as and for the purpose described.

30 3. In a car-coupler, the combination of a draw-head provided with two vertical recesses

for receiving the bearings of the dogs, said dogs having slots or holes for the passage of the coupling-pin, and a removable cover or top piece hinged to the draw-head and fitting 35 into a corresponding recess in the same and having its rear end beveled, as and for the purpose described.

4. In a car-coupler, the combination of a draw-head provided with two vertical recesses 40 extending from the top to bottom for receiving circular bearings projecting from each side of the dogs, said bearings resting upon each other, allowing spaces between the dogs for the passage of the coupling-link, and a removable cover or top piece hinged to lugs or bearings formed upon the top of the draw-head, as and for the purpose described.

5. In a car-coupler, the combination of the draw-head provided with two vertical recesses 50 for receiving the bearings of the dogs, said dogs having slots or holes for the passage of the coupling-pin, and a removable cover hinged to the draw-head, provided with two lugs or projections, as and for the purpose described. 55

In testimony whereof I affix my signature in presence of two witnesses.

WILLIAM A. MACOMB.
